[57] **CLAIM**

The ornamental design for an article carrier attachable to footwear, as shown and described.

DESCRIPTION

FIG. 1 is a perspective view of an article carrier attachable to footwear, showing my new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a bottom plan view thereof;

FIG. 7 is a rear elevational view thereof; and,

FIG. 8 is a perspective view showing the pockets thereof in an open position.

The broken-line showings of footwear and lace in FIG. 1 are environmental only and form no part of the claimed design.
